UNITED STATES PATENT OFFICE

JAMES ALLEN, OF THE UNITED STATES ARMY.

RELAY.

No. 814,501.

Specification of Letters Patent.

Patented March 6, 1906.

Application filed July 31, 1905. Serial No. 271,968.

To all whom it may concern:

Be it known that I, JAMES ALLEN, colonel, Signal Corps, United States Army, a citizen of the United States, residing at Washington, 5 in the District of Columbia, have invented certain new and useful Improvements in Relays; and I do hereby declare the following to be a full, clear, and exact description of the invention, such as will enable others skilled in 10 the art to which it appertains to make and use the same.

This invention relates to improvements in relays; and it consists in the novel combination and arrangement of parts herein described, and more particularly pointed out in the accompanying claims.

Referring to the accompanying drawings, Figure 1 represents in top plan a form of relay embodying my invention, and Fig. 2 a 20 detail perspective of retaining-armature.

In carrying out the form of my invention shown I provide a preferably permanent horseshoe field-magnet 1, having pole-pieces 2. Within the field of this magnet and between the pole-pieces 2 is mounted for deflective movement either upon pivots or suspensions in any of the well-known ways a coil system 3. The coil 3 may move around a stationary soft-iron core 4, supported upon a 30 non-magnetic support 5, as in the well-known D'Arsonval galvanometer or Weston movable coil instruments.

Mounted for movement by and with the coil 3 is a tongue 6, preferably of some light 35 non-magnetic metal. One end of this tongue is adapted to move between two adjustable contacts 7 and 8, mounted upon supports 9 and 10, respectively, secured to and insulated from the magnet, as shown.

40 The combination of parts thus far described in detail is old. Such a relay, however, while being delicate, is totally unfit for a certain character of work—viz., that in which a polarized relay or one fulfilling the functions 45 of a polarized relay is required, and more especially when the relay is to be worked by induced or secondary currents or to be used in a circuit in which there is a condenser. In such cases it is essential that the relay-tongue 50 remain against the contact to which it was last sent after the actuating-current has died out or is insufficient by itself to longer hold the tongue against the contact. This hold-over action is secured in the common form of

polar relay by means of a permanently-polarized armature movable between the poles of an electromagnet. 55

I accomplish the same result in the present form of relay by mounting a small soft-iron armature 12 for movement by and with the 60 movable coil between two auxiliary adjustable pole-pieces consisting in the case illustrated of two steel screws 13 and 14, mounted in iron or steel supports 15 and 16, made fast to the pole-pieces 2. The armature may be 65 secured to the movable coil in a number of ways. In the case illustrated this is effected by providing the tongue 6 with an extension 17, to which the armature is rigidly fixed, as at 18. 70

Current from the main operating-circuit (indicated in part by wires 19) may be led into and out of the movable coil by small flexible leads, as shown, or in any other suitable way. The relay-circuit is connected by wire 20 to 75 the tongue 6 in any desired manner and by wire 21 to one of tongue-contacts. It will therefore be seen that when current traverses the coil 3 in one direction its angular motion will send the tongue 6 against one of the contacts. At the same time one of the ends of the armature 12 will be sent toward one of the adjustable pole-pieces 13 14, by which the said armature will be attracted and held until a current is passed through the coil 3 in 80 an opposite direction of sufficient strength to overcome the pull of the magnet on the armature 12, when the tongue will be thrown to the opposite contact and the armature 12 to the opposite adjustable pole. 85 90

It will be seen that the current to move the coil must be strong enough to overcome the pull of the auxiliary pole-pieces. Therefore if the tongue is sent over against a given contact by current through the movable coil a 95 succeeding though very feeble current, not intended for the operation of the instrument, would cause the tongue to be sent against the opposite contact were it not for the pull of the auxiliary poles, which this weaker current 100 would have to overcome.

The above characteristics render this instrument particularly well adapted for cable use and also for use on board ships or on any other body subject to a vibrating motion 105 which would be apt to shake the relay-tongue back and forth between its contact-stops. I do not, however, confine my invention to the

type of instrument shown, as it may be made in many forms without departing from the spirit of my invention; but

What I do claim is—

5. 1. A relay having a system mounted for deflective movement in a magnetic field, an armature mounted for movement by said system and independent of the magnetization of said system, and a pair of pole-pieces between which said armature is adapted to oscillate.
10. 2. A relay having a coil system mounted for deflective movement in a magnetic field, a soft-iron armature mounted for movement by said system and independent of the magnetization of said system, and a pair of adjustable pole-pieces between which said armature is adapted to oscillate.
15. 3. In a relay, the combination with a magnet, of a coil mounted for deflective movement between the poles of said magnet, a contact-tongue mounted for movement by said coil, contact-stops for said tongue, an armature mounted for movement by said system and independent of the magnetization thereof, and a pair of auxiliary adjustable pole-pieces between which said armature is arranged to oscillate.
20. 4. In a relay, the combination with a permanent magnet, of a coil mounted for deflective movement between the poles of said magnet, a contact-tongue of non-magnetic conducting material mounted for movement by said coil, contact-stops for said tongue, a soft-iron armature operatively connected to said tongue and coil but independent of the magnetization of said coil, and a pair of adjustable pole-pieces between which said armature is arranged to oscillate.

ture mounted for movement by said coil but independent of the magnetization thereof, 25 and a pair of auxiliary adjustable pole-pieces between which said armature is arranged to oscillate.

4. In a relay, the combination with a permanent magnet, of a coil mounted for deflective movement between the poles of said magnet, a contact-tongue of non-magnetic conducting material mounted for movement by said coil, contact-stops for said tongue, a soft-iron armature operatively connected to said tongue and coil but independent of the magnetization of said coil, and a pair of adjustable pole-pieces between which said armature is arranged to oscillate.

In testimony whereof I affix my signature 40 in presence of two witnesses.

JAMES ALLEN.
